UNITED STATES PATENT OFFICE.

REGINALD LIONEL POWELL, OF CAWNPORE, INDIA.

RAILWAY-SIGNAL MIDWAY WIRE-COMPENSATOR.

1,272,314.

Specification of Letters Patent.

Patented July 9, 1918.

Application filed March 10, 1917. Serial No. 153,873.

To all whom it may concern:

Be it known that I, REGINALD LIONEL POWELL, a subject of the King of Great Britain and Ireland and Emperor of India, 5 residing at Cawnpore, India, have invented new and useful Railway-Signal Midway Wire-Compensators, of which the following is a specification.

This invention is intended to compensate 10 signal wires which being subject to atmospheric influences alternately expand and contract, when affected by heat or cold during the varying temperatures of the day and night.

15 The contraction of wires has the effect of involuntarily lowering signals without being worked by the signal man and the obvious danger to human life that may result from such a condition of things is apparent, 20 as signals normally "at danger" might be released by the contraction and collisions occur.

On the other hand the expansion of signal wires, does not allow of signals being 25 sufficiently lowered to the proper degree, and as drivers have strict instructions to treat signals not fully lowered as still "at danger" detentions to trains and consequent dislocation of traffic working results.

30 My invention is illustrated in the accompanying drawings in which:

Figure 1 shows the compensator fitted and in working order.

Fig. 2 shows the side view of the compensator.

Fig. 3 shows the front view of the compensator.

The compensator is fixed midway between the lever A and the signal, and takes up the 40 expansion and contraction of the wires, leaving the signal in its normal or danger position.

The length of the wire from B to D is equal to the length of the wire from O to Q.

45 1 is the standard or post to which a bracket L is fixed.

M and N are weighted cranks, which work as also the floating lever H on a pivot 2 fixed to the bracket L. E and K are the 50 weights fixed to the cranks M and N respectively by stud bolts and blocks.

G and I are links the upper ends of which are pivoted to the cranks M and N respectively at F and J; the lower ends of the

links are connected to the floating lever H 55 by means of a pin U, which passes through the slots in the links, and the slot in the floating lever H.

The link G has a slot of about 2 inches in length, and at the end on its under surface a stud pin T is fixed. The stud pin T, engages in the teeth of the floating lever H, as will be explained hereafter. The link I has a slot from a little below the fork end to nearly the end of the link. The object 60 of this slot in the link I is to compensate for any unusual tension in the wire O Q which may occur when the weight R is moved for oiling and cleaning the weight arm on the signal.

S is a stop fixed to the standard or post, and prevents the floating lever H from passing that point. V is a spring attached to the bracket L and engages the upper end of the floating lever H.

70 The compensator acts in the following manner: When the signal is in its normal or danger position, the lever A being in its normal position, the cranks M and N are free to take up any expansion or contraction of the wires. If any contraction of the said wires take place, the cranks M and N at the points D and O work inward to one another, without in any way affecting the signal arm. This is clear as the actual length considered 80 as a whole from the point B to Q remains the same, as what is lost by contraction is compensated for by the movements of the points D and O, so that the tension on the wires remains practically the same as it was before the contraction took place. The points D and O working inward to one another, causes the weights E and K to rise,

as the weight on the signal at R is heavier than the weight K on the crank N. The links G and I therefore work upward carrying with them the pin U which works in the slot of the floating lever H. Similarly if the signal wires expand the cranks M and N at the points D and O work outward from one another to the extent the wires have expanded and the weights E and K move downward by gravity to take up the slack in the wires due to the expansion, the links G and I working downward, the pin U working in the slot of the floating lever H 90 as already described.

100 The action of the compensator when the

lever is pulled over to lower the signal is as follows:

The tension on the wire, when the lever A is pulled over causes the point D of the 5 crank M to work inward, and the upper end of the crank M with weight E works upward, drawing up the link G, the link G has an escapement of about 2 inches and works or slides diagonally for that distance, 10 when the stud pin T engages in a tooth of the floating lever H. As soon as the stud pin T engages, the escapement ceases. The engagement of the stud pin T in a tooth of the floating lever H fixes the links G and I 15 so that the links, together with the cranks M and N and the floating lever H will now act as a fixed or single piece working on the pivot 2 from which the cranks M and N and the floating lever H are suspended, so 20 that a further pull of the lever A causes them to work as a whole in a circular motion upward *i. e.* in the direction of the hands of a clock; the lower end of the crank N at O is therefore forced outward and upward, 25 thereby pulling the signal wire from O to Q and so lowering the signal.

When the lever A is put back the action of the compensator is as follows:

The release of the tension on the wire 30 causes the weight E to descend thereby working the lower end of the crank M at the point D outward and the link G and the floating lever H downward in a circular motion *i. e.* opposite to the hands of a clock, the link I 35 and the crank N, also moving in their proper direction, being part of the fixed piece formed by the engagement of the stud pin T, as already described. As soon as the floating lever H rests against the stop S, the link 40 I and the crank N stop working, having gone fully home, but the crank M and the link G work about another 2 inches and thereby release the stud pin T from the floating lever H, and also release the cranks M and N 45 from each other, which are again free to do their compensation.

I claim:—

1. A railway signal wire compensator, comprising weighted cranks to which are attached respectively the wires leading to the 50 signal and signal lever, a member having limited swinging movement, and a connection between each crank and one end of the

swinging member, whereby all the said parts will swing together. 55

2. A railway signal wire compensator, comprising weighted cranks mounted on a common pivot and to which are attached respectively the wires leading to the signal and signal lever, a swinging member mounted upon the pivot of the cranks, and a connection between the cranks and swinging member. 60

3. A railway signal wire compensator, comprising two weighted cranks mounted on a common pivot and to which are attached respectively the wires leading to the signal and signal lever, a swinging member, and a connection between the swinging member and the members of the cranks carrying the 70 weights. 65

4. A railway signal wire compensator, comprising two weighted cranks to which are attached respectively the wires leading from the signal and signal lever, a floating lever, 75 links pivoted to the cranks and pivotally and slidably connected with the floating lever, and a stop for said lever.

5. A railway signal wire compensator, comprising two weighted cranks to which are attached respectively the wires leading from the signal and signal lever, a pivoted and spring pressed floating lever provided with teeth, a stop for said lever and links pivoted to the cranks and pivotally and slidably connected with the floating lever, one of the links being provided with a stud or pin for engaging the teeth of the floating lever. 80 85

6. A railway signal wire compensator, 90 comprising two weighted cranks to which are attached respectively the wires leading from the signal and signal lever, a pivoted and spring pressed floating lever provided with a longitudinal slot and teeth, a stop 95 for said lever, links pivoted at one end to the cranks and having their other ends provided with slots, one of the links being provided with a pin for engaging the teeth of the floating lever, and a pin passing through 100 the slots of the links and floating lever.

19th January, 1917.

REGINALD LIONEL POWELL.
